UNITED STATES PATENT OFFICE.

ARTHUR R. McARTHUR AND EDWIN EARL MOORE, OF GARY, INDIANA, ASSIGNEES
TO AMERICAN SHEET AND TIN PLATE COMPANY, OF PITTSBURGH, PENNSYLVANIA, A CORPORATION OF NEW JERSEY.

HEATING FURNACE.

Application filed December 27, 1927. Serial No. 242,674.

This invention relates to heating furnaces and, while not limited thereto, relates more particularly to a heating furnace for sheets and packs of sheets, and has for its object 5 the provision of a furnace of the class described which will require materially less labor to operate, will be more efficient than the furnaces of the prior art, and one in which the sheets and packs will be concentrated 10 under the observation of the roller at all times.

In the drawings—

Figure 1 is a longitudinal sectional elevation, partly broken away, of a furnace constructed in accordance with this invention.

Figure 2 is a sectional elevation on the line II—II of Figure 1.

Figure 3 is a diagrammatic elevation of the driving gears.

20 Figure 4 is an enlarged fragmentary sectional elevation of the forward end of the furnace, showing the feed and discharge conveyors.

Figure 5 is an elevation of the forward end 25 of the furnace showing the conveyors.

Figure 6 is an enlarged sectional elevation of the rear end of the furnace showing the transfer mechanism.

Figure 7 is a rear end elevation of the 30 furnace.

Referring more particularly to the drawings, the letter A designates the furnace as a whole, which comprises a heating chamber B and combustion chambers C and D. Gas 35 burners 2 and 3 enter the respective combustion chambers C and D and are connected to gas supply flues 4 and 5, respectively.

The burners 2 and 3 are connected to air 40 lines 6 and 7 which supply preheated air to support combustion, and these air lines are extended through channels 8 in the roof 9 of the furnace so as to preheat the air. It will be understood, that if desired, other means may be employed for preheating the air than 45 that shown.

The forward end of the heating chamber B is provided with separate vertically spaced ingoing and outgoing ports or openings 10 and 12 through which the packs or sheets 50 to be heated enter and leave the furnace, respectively.

The sheets and packs are delivered to and through the ingoing port or opening 10 by conveyors 13 and 14 which are automatical-

ly controlled by switches 15 and 16, operated by triggers 17 and 18 which extend into the path of and are operated by the packs or sheets as they pass over the respective conveyors 13 and 14.

The switches 15 and 16 are adapted to control the operation of the conveyors 13 and 14 so as to cause the packs or sheets to be fed into the furnace with a minimum distance between each pack or sheet, regardless of the width or length of each. The conveyor 13 runs at 60 a fast speed causing the packs or sheets to be accelerated onto the conveyor 14 against an adjustable stop 19 while the conveyor 14 runs at a relatively slow speed.

The packs or sheets as they are conveyed 70 along the conveyor 13, will contact with the trigger 17 and operate the limit switch 15 to stop the conveyor 13 if a pack or sheet is passing over the trigger 18 on the conveyor 14 which operates the switch 16. The switch 15 75 is by-passed with the switch 16 so that if no pack or plate is on the conveyor 14 the operation of the switch 15 will not affect the conveyor 13. However, if a pack or sheet is on the conveyor 14 and in engagement with the trigger 18, the conveyor 13 will remain stationary until the pack or sheet passes over the trigger 18.

A pair of vertically spaced conveyor tables 80 X and Y are arranged within the furnace in line with the vertically spaced ingoing and outgoing openings 10 and 12, respectively.

The table X is composed of a plurality of shafts 21 journaled in bearings 22 on the outer frame of the furnace, and each of said shafts 85 23 carries a plurality of conveyor rollers or disks

The table Y is composed of a plurality of shafts 24 journaled in bearings 25 on the outer frame of the furnace, and each of said shafts 90 26 carries a plurality of conveyor rollers or disks 26.

The tables X and Y are operated from a single source of power, shown as a motor 27, through a gear unit 28 which drives lower 100 and upper drive shafts 29 and 30 in opposite directions.

The lower or ingoing table X is divided into a slow unit X¹ and a fast unit X², and the upper or outgoing table Y is divided into two fast units, Y¹ and Y², at each end, and an intermediate slow unit Y³.

The shafts 21 of the slow unit X¹ of the

table X are connected to the lower drive shaft 29 by worm and worm-wheel connections 31, while the shafts 21 of the fast unit X² are connected to the shaft 29 by spiral gearing 32.

The shafts 24 of the slow unit Y³ of the table Y are connected to the upper drive shaft 30 by worm and worm-wheel connections 33, while the shafts 24 of the fast units

10 Y¹ and Y² are connected to the shaft 30 by spiral gearing 34.

The fast unit X² of the table X causes the packs or sheets traveling through the furnace to move quickly away from the one 15 following when approaching the kick-up mechanism, to be described.

The fast unit Y² of the table Y causes the packs or sheets to be accelerated onto the slow unit Y³ of the table Y when such sheets 20 or packs are delivered by the kick-up mechanism, and the fast unit Y¹ accelerates the packs or sheets from the table Y onto a discharge conveyer 36.

A kick-up or transfer mechanism for trans- 25 ferring the packs or sheets from the lower table X to the upper table Y comprises a tilting table 37 which is pivotally supported on a transverse shaft 38 at the rear end of the furnace, and has a plurality of bars which 30 normally extend along the lower table X between the disk rollers. The rear end of the table 37 is provided with a pair of operating arms 39 which project outwardly through slots 40 in the rear end of the furnace, and 35 are connected to a crank-shaft 41 by links 41^a. The shaft 41 is driven by a motor 42 through a worm-gearing 43.

A kick-up or kick-off arm 44, having a hinged finger 45, is pivotally supported on a 40 transverse shaft 46. A lever arm 47 is mounted on one end of the shaft 46 and connected by a rod 47^a to a crank disk 47^b on the shaft 41, so as to cause the arm 44 to oscillate to kick or push the packs or sheets from the 45 tilting table 37 onto the table Y.

An adjustable trigger 48 is extended through the rear wall of the furnace into the path of the packs or sheets as they move onto the tilting table 37. The trigger 48 is connected to a bell-crank lever 49 which is pivoted about a centering point 50 and adapted to operate a limit switch 51. Closing of the switch 51 causes the motor 42 to drive or rotate the shaft 41.

55 A disk 52 is mounted on the shaft 41 in contact with a roller 53 on the lever arm 49, so that when the shaft 41 is caused to rotate the disk 52 will, by means of its shape, hold the lever 49 in position to maintain the switch 51 closed until the shaft 41 has made one complete revolution.

A hand-wheel 55 is provided for setting the position of the trigger 48 to suit the varying lengths of packs or sheets.

65 A master control trigger 56 is pivotally

supported on a transverse shaft 57 adjacent the outlet opening 12 and is adapted to be operated by the packs or sheets as they approach the outlet opening. The shaft 57 is adapted to operate a master limit switch 58, which 70 switch, when operated by the shaft 57, will break all circuits to the operating motors of the furnace so as to stop the travel of all sheets or packs through the furnace.

The switch 58 is adapted to be by-passed by 75 the mill roller operating a by-pass switch (not shown) when he desires another pack or sheet and, therefore, the entire furnace is under the control of the mill roller.

In operation, the packs or sheet will be delivered by the conveyer 13 onto the conveyer 14. After one pack has been delivered onto the conveyer 14 and has engaged the trigger 18, a second pack or sheet moving along the conveyer 13 and engaging the trigger 17 will 80 operate the switch 15 to stop the conveyer 13 until the preceding pack or sheet has moved from the conveyer 14 and released the trigger 18 operating the switch 16.

The conveyer 14 will deliver the packs or 90 sheets onto the unit X¹ of the table X which will convey the packs or sheets slowly through the furnace until the unit X² of the table is reached, when the leading pack or sheet will be accelerated, drawing away from 95 the succeeding packs or sheets. When the preceding accelerated pack or sheet strikes the trigger 48, the switch 51 will be closed to energize the motor 42 which will in turn operate to rotate the shaft 41.

Rotation of the shaft 41 will cause the table 37 to elevate to raise the pack or sheet from the unit X² of the table X and the kick-off arm 44 will be moved forward to push or slide the pack or sheet from the 105 transfer table 37 onto the conveyer table Y. The shaft 41 will then complete its revolution and return the parts to normal position to receive the next succeeding pack or sheet.

The sheets or packs delivered onto the 110 table Y will be slowly conveyed along the unit Y³ until engaged by the fast unit Y¹ at which time they will engage the master control trigger 56 and operate the trigger so 115 as to open the master switch 58 and stop all the furnace parts. All the parts of the furnace will remain inactive until the mill roller closes a by-pass switch (not shown) which will by-pass the switch 58 and again start 120 the furnace in operation.

When the roller again starts the furnace in operation the fast unit Y¹ of the table Y will accelerate the pack or sheet onto a conveyer 36 which will convey the pack or sheet 125 by gravity to the roll stand.

While we have shown and described one specific embodiment of our invention, it will be understood that we do not wish to be limited thereto since various modifications 130

may be made without departing from the scope thereof, as defined in the appended claims.

We claim—

- 5 1. In a sheet and pack heating furnace, a heating chamber, said chamber being provided with inlet and outlet openings, said outlet opening being spaced above said inlet opening, an in-going conveyer table extending through said heating chamber from said inlet opening, an out-going conveyer table extending through said heating chamber from said outlet opening in vertical spaced relation above said in-going conveyer table, and means operable by the sheets and packs for elevating and feeding the sheets and packs from said in-going conveyer table onto said out-going conveyer table.
- 10 2. In a sheet and pack heating furnace, a heating chamber, said chamber being provided with inlet and outlet openings, said outlet opening being spaced above said inlet opening, an in-going conveyer table extending through said heating chamber from said inlet opening, an out-going conveyer table extending through said heating chamber from said outlet opening in vertical spaced relation above said in-going conveyer table, and means operable by the sheets and packs including a tilting-table and kick-off arm for elevating and feeding the sheets and packs from said in-going conveying table onto said out-going conveyer table.
- 15 3. In a sheet and pack heating furnace, a heating chamber, said chamber being provided with inlet and outlet openings, said outlet opening being spaced above said inlet opening, an in-going conveyer table extending through said heating chamber from said inlet opening, an out-going conveyer table extending through said heating chamber from said outlet opening in vertical spaced relation above said in-going conveyer table, and means comprising a tilting-table and pushing mechanism for transferring the sheets and packs from one of said tables to the other of said tables.
- 20 4. In a sheet and pack heating furnace, a heating chamber having an inlet and outlet opening at one and the same end, one of said openings being spaced above the other, roller conveyer tables in said chamber and spaced one above the other in line with said openings, a tilting transfer table adapted to elevate the sheets and packs from the lower table to the upper table, and means for moving the sheets and packs from said transfer table onto said upper table.
- 25 5. In a sheet and pack heating furnace, a heating chamber having an inlet and outlet opening at one and the same end, one of said openings being spaced above the other, roller conveyer tables in said chamber and spaced one above the other in line with said openings, a tilting transfer table adapted to elevate the sheets and packs from the lower table to the upper table, means operable by the sheets and packs for controlling the operation of said tilting-table, and automatic means for moving the sheets and packs from said tilting-table onto said upper table.

In testimony whereof, we have hereunto signed our names.

ARTHUR R. McARTHUR.
EDWIN EARL MOORE.
